UNITED STATES PATENT OFFICE.

JOHN EDWARD GLOEKLER, OF PITTSBURG, PENNSYLVANIA.

DESIGN FOR A STAND.

41,431.

Specification for Design.

Patented June 6, 1911.

Application filed March 18, 1911. Serial No. 615,447. Term of patent 14 years.

To all whom it may concern:

Be it known that I, JOHN EDWARD GLOEKLER, a citizen of the United States, residing at Pittsburg, in the county of Allegheny and State of Pennsylvania, have invented a new, original, and ornamental Design for Stands, of which the following is a specification, reference being had to the accompanying drawing, forming part thereof.

The figure is a view of a stand, showing my new design.

I claim:

The ornamental design for a stand, as shown.

JOHN EDWARD GLOEKLER.

Witnesses:

OSCAR BRASHEAR,
WM. H. BAUMANN.
